UNITED STATES PATENT OFFICE.

ROBERT L. OMENSETTER, OF PHILADELPHIA, PENNSYLVANIA.

IMPROVEMENT IN RAILROAD CAR VENTILATORS.

Specification forming part of Letters Patent No. 124,613, dated March 12, 1872.

Specification describing certain Improvements in Car-Ventilators, invented by ROBERT L. OMENSETTER, of the city of Philadelphia and State of Pennsylvania.

The nature of my invention consists in making the ventilating-flues in the sides of the car open at bottom and combining therewith deflecting-plates. The forward motion of the car has the tendency of forming a vacuum in the flues, and thereby to draw the air through them from the interior of the car to ventilate the same. The deflecting-plates are hung on pivots in such a manner, that the forward motion of the car causes them to come into the right position to turn the current of air below the car that would otherwise rush up the flues, as hereinafter described.

Figure 1 is an inside view of a portion of a car, showing a window, A, and side panels B on my improved plan. Fig. 2 is a vertical section, at the line $x x$ of Fig. 1. Fig. 3 is a like view, at the line $y y$ of Fig. 1. Fig. 4 is an isometrical view of one of the valves F.

Like letters in all the figures indicate the same parts.

There are vertical ventilating-flues G at each side of the windows open at bottom, which communicate with the interior of the car at their upper ends by means of openings H. The

forward motion of the car creates a current of air to the rear of the same, and passing under the flues by its suction tends to form a vacuum in each flue, thereby causing an inflowing of air so as to keep up a circulation. To make the downward current more complete, the air is prevented rushing into the bottom of the said side flues by means of the valves F. These valves swing freely on the pivots a , so that the current of air striking against the lower end turns the valve when the car is moving in the direction indicated by the arrows, into the position represented in Fig. 1, thereby closing that portion of the flues in front of the valves and deflecting it downwards, and thus preventing it rushing in the rear of the same up the flues. The openings H may be provided with registers for regulating the draught through the flues G'.

I claim as my invention—

The combination and arrangement of the pivoted valves F with the lower ends of the flues G', for deflecting the currents of air as they pass beneath the same, so as to prevent the air from passing up the flues, as specified.

ROBERT L. OMENSETTER.
